UNITED STATES PATENT OFFICE

PAUL ARTHUR HIRSCH, OF NEW YORK, N. Y.

OUTFEEDING MEANS FOR FUEL PULVERIZING MACHINES

Application filed June 1, 1926. Serial No. 112,956.

This invention is a novel outfeeding means for pulverizing machines, having reference particularly to the pulverizing of coal, or other fuels. The invention is herein shown embodied in a type of pulverizing machine having a chambered casing, with an operating shaft therein, and impact beaters or paddles revolved by the shaft, while axial air flow causes progressive advance of the material being reduced; although features of the present invention may be otherwise embodied. A prior pulverizer of the type and for the purpose referred to, is illustrated in my Patent No. 1,479,540 of January 1, 1924.

One of the main objects of the present invention is to improve the delivery of the pulverized material from the machine, namely into a delivery or fan chamber, and the discharge thereof from the fan chamber, and in the case of fuel the admixture thereof with additional quantities of air of combustion; this involving a novel structure of delivery means or fan and the novel method or mode of operation secured thereby.

Other and further objects and advantages of the present invention will be explained in the hereinafter following description of an illustrative embodiment thereof, or will be apparent to those skilled in the art. To the attainment of the objects and advantages referred to the present invention consists in the novel method and machine, and the novel features of operation, combination, arrangement and construction herein illustrated or described.

In the accompanying drawings Fig. 1 is substantially a central vertical cross section of a pulverizing machine illustrating the present invention, the fuel and air infeed shown at the right end and the delivery means at the left end of the figure.

Fig. 2 is a detail perspective view showing one of the pulverizing members, beaters or paddles of this invention, and its relation to the fast rotating wheel or disk which carries it.

Fig. 3 is a right elevation taken partly in section on the line 3—3 of Fig. 1 and showing the preferred construction of the delivery fan or blower.

Fig. 4 is a partial perspective view of a peripheral portion of the rotary fan or blower.

Referring in detail to the illustrated structure Fig. 1 shows a pulverizing machine of the horizontal type, the same as my aforesaid Patent 1,479,540, although in some cases it could as well be arranged vertically as in my other Patent 1,479,541 of the same date. Mounted on a base 11 is shown a cylindrical drum or casing 12 preferably fixed against rotation. The drum may be constructed in two or three radially divided sections for the purpose of assembly, disassembly and transportation. The lower right hand part of the casing is shown as having a dropped extension 14 in which foreign material may be collected as will be described, a removable cover or receptacle 15 being attached to the open side of the extension by which the foreign material may be removed from time to time. The drum or casing encloses successive chambers or spaces and is shown as lined with a steel lining or ring 17 in each of the pulverizing spaces or chambers, the right hand one of these linings being perforated at 18 above the extension 14 to permit heavy and foreign material to be discharged from the chamber into the extension.

The drum at its right end is closed by a circular end wall or casting or head 19 having a central or axial opening 20 by which the material to be pulverized can enter the drum. The head 19 is shown formed with an extension 21, the lower part of which is inclined

so as to facilitate the infeed of material to the pulverizer and the descent of heavy foreign materials toward the extension 14. The extension 21 is further shown as giving support to one of the bearings 24 of the operating shaft 25, the other end of the shaft having a similar bearing 26 supported upon a fixed frame extension or bracket 33. The driving shaft 25 may be rotated at high speed through its exterior extension 28 in any desired manner, for example through belt and pulley or direct coupled motor, turbine or the like.

The left or discharge end of the drum is shown as closed by an end wall or head 29

having a central or axial opening 30 of relatively contracted diameter, through which the pulverized materials and air may pass out from the drum to the delivery or fan chamber. 5 The pulverizing is preferably done wholly inside the drum, while the air draft for the final discharge and dilution of the pulverized materials is provided by a suction fan or blower located beyond the pulverizing chambers, and exterior to the pulverized discharge wall or head 29. For this purpose a fan casing 31 is shown, which may conveniently be integral with the head 29. The bracket support 33 for the bearing 26 may also be integral with the fan casing. The fan casing has also a peripheral extension 34 providing a tangential exit passage or discharge 35, analogous to that shown in said prior Patent 1,479,540, but herein shown directed upwardly, as is frequently necessary for blowing out or delivering the mixed fuel and air to a furnace. 20

The infeed of the fuel may be by a hopper 37, suitably supplied with coal or other material after preliminary grinding to a suitable size. The hopper 37 loads to a regulatable feed comprising a rotated star wheel 38 bringing successive fuel portions into the following passage 39, the materials passing downwardly by gravity into the separating chamber 41, the walls 42 of which may be integral extensions of the casting 21 containing the central inlet aperture 20. One of the walls 42 may contain an opening 43 for the admission of air, and it will be understood that any of the air admission opening or ports may be regulatable by a damper. Within the chamber 41 may be any suitable separating means such as a magnetic shell 44 turned continuously by a shaft 45, these parts indicated in dotted lines. Electromagnets within the shell may maintain a condition of strong magnetism so that all iron particles will be caused to adhere strongly to the shell and thus carried around to the outer portion of the chamber, where they are progressively detached from the shell by the scraper or flange 46, thus depositing the iron particles in the receptacle 47 from which they may be removed through the aperture 43. The shafts of the star feed wheel 38 and of the magnetic shell 44 may be suitably driven in synchronism during the operation of the pulverizer, and the speeds may be adjustable in any usual manner to regulate the rate of fuel feed, a slower rate of feed being accompanied by a greater degree of pulverization. The fuel passing through the separating chamber 41 descends into the passage 48 in the extension 21, a plate 49 acting as a shield to insure the materials entering with a descending motion or preventing their entering into the first pulverizing chamber above the operating shaft. 60

65 There may be a single pulverizer chamber

within the drum, or a series of them, and Fig. 1 shows a first reduction chamber 51 and a second reduction chamber 52, within which the fuel will be progressively pulverized by the fast rotating beating means mounted within each chamber upon the shaft 25. Thus the shaft is shown as having pinned or keyed to it in each chamber a hub 54 on which is mounted a disk 55, around the circumference of which are mounted a series of peripheral beaters or paddles 56. Such a beater structure has been already explained in said prior patent, although the structure of the beater hereof is considerably improved with resulting increase of efficiency and length of life, as will be explained. 75

Located between the first and second pulverizing chambers 51 and 52 is shown a means for effecting a sudden obstructing of the whirling motion produced by the fast rotating paddles in chamber 51. This whirl obstructor may be in the form of a series of blade-like vanes 60 set edgewise to the axial advance of the material and extending from or near the periphery of the chambers to or toward the shaft. Preferably the vanes 60 are relatively stationary, and they may stand radially or otherwise. The action of such vanes has been described in said prior patent. The several vanes may be mounted and interconnected by means of a peripheral ring 61 attached to the lining 17, and an inner ring 62 loosely surrounding the shaft 25. 90

Beyond the second pulverizing chamber 52 and between it and the fan casing is shown another set of obstructing vanes 65, with an outer ring 66 interconnecting them. These have a special function herein, in addition to the function possessed by the vanes 60; 105 this to be explained more fully hereinafter. An inner ring 67 unites the inner ends of 65.

It will be noticed that within and between the pulverizing chambers there are no annular or other division walls or so-called diaphragms, nor any substantial obstruction to the axial progress of the materials, between the axial entrance aperture 20 in the head 19 and the axial exit aperture 30 in the head 29. This aperture 30 is of considerably less diameter than the pulverizing chambers, and of less diameter even than that of the pulverizing elements, that is, the diameter from tip to tip of the paddles. In these and other respects to be explained the present invention is materially different from said prior patent and other prior structures of which I am familiar. The aperture 30, indeed, is shown of such small diameter that materials progressing through it pass into the interior of the rotary fan structure, an important consideration. 110

The fan chamber 32 may be almost of the full diameter of the main casing, as shown, but the fan 70 is preferably of considerably 125

smaller diameter. It is shown mounted on a hub 71 keyed to the shaft 25. A novel and efficient fan construction is shown wherein the hub 71 carries a disk or circular plate 72, opposite to which is a ring or annular plate 73, the disk and the ring supporting, and being interconnected by, a series of fan blades 74. With this invention the blades 74 are arranged to handle the supplemental air of combustion which may be introduced into the fan chamber 32 by way of the axial inlet 36, which may be damper governed, the air being drawn in and whirled centrifugally through the fan chamber and out by the discharge 35; while the pulverized material or fuel and its carrying stream of air are handled by a separate set of blades or vanes 76 mounted at the inner or right hand side of the disk 72. It is intended that there shall be an entire series of fuel vanes 76, spaced around the periphery of the disk 72 in the manner indicated in Figs. 3 and 4. Each blade 76 may constitute the flange or bent portion of a plate or base 77, which latter may adjustably be mounted on the disk near its periphery by means of an outer bolt or pivot 78, the plate formed with a concentric slot 79 engaged by an inner bolt 80 engaged in a threaded perforation 81 in the disk. By this arrangement the fuel whirling fan blades 76 may be adjusted in their angle and operation. Figs. 3 and 4 show two different angular adjustments of these members, while Fig. 3 in dot-and-dash lines shows the two extremes of adjustment as preferably used. It will be observed that the fuel whirling blades 76 are slanted from the radius, whereas the supplemental air whirling blades 74 are preferably radial. The slant of the blades 76, and the means of adjustment thereof, afford an advantageous action as will be described.

The paddles, hammers or beaters 56 are herein constructed and mounted in a novel manner giving substantial advantages. In the hammer mounting of said prior patents the continuity of the surfaces of the supporting disks is substantially interrupted near the periphery by protruding portions of the paddles and the bolts by which they are mounted. By comparative tests it has been found that these protruding elements are not merely the source of wear and expense, but owing to their being in the path of the centrifugally flowing powdered materials they cause a disturbance of the flow and impair the efficiency of the reducing action. These objections are wholly overcome by the present construction in which the sides of the disk are uninterrupted by protrusions and the whirling materials are able to pass smoothly outwardly into the paths of the beaters or paddles, rendering the beating action more thorough and actually resulting in a greater fineness of pulverization and increased capacity of the machine, with reduced power.

The paddles or beaters are shown in their relative arrangement in Fig. 1, and the preferred details of structure in Fig. 2. Each paddle comprises a T-shape body 85, mounted preferably swingably at the periphery of the disk 55. The enlarged portion or head of the paddle body 85 is formed with an outer flange 86, and a removable paddle face plate or block 87 is provided with a shoulder 88 engaging the flange 86, giving an interlocking action, and enabling the centrifugal thrust of the blocks 87 to be received by the flange 86 without any shearing strain upon the bolts 89 by which the block is secured to the body. The forward side or face 90 of the block 87 is shown inclined forwardly giving an effective beating action and allowing for wear by abrasion at a greater rate near the periphery of the block without substantially impairing the effectiveness of the action. The thin web portion 91 of the paddle body 85 is perforated and in use is arranged in a recess in the periphery of the disk 55, so as not to protrude beyond the flush surface of the disk. This recess is preferably in the form of a kerf 92, and there may be a separate recess or kerf for each of the paddles, or there may be a continuous kerf or groove extending entirely around the peripheral edge of the disk 55. The web 91 is held in place in the kerf 92 by means of a transverse stud 93, which may be a simple pin without head at either end, and this stud in turn may be held against displacement by a cotter pin 94, screw or other means securing it to the web 91 of the paddle.

Instead of a single integral disk 55 provided with an edge groove or kerf 92, this disk may be built up, for example by two circular plates spaced slightly apart to accommodate the paddle shank between them. While only two paddles are shown on each disk there may be the usual plural number, e. g. between 12 and 18, or even as low as 8 and as high as 24.

The paddle construction so described attains the advantages referred to. All wear is practically eliminated excepting upon the face plates or blocks 87 which are readily renewable, so that the life of the apparatus and the ease of renewal are greatly enhanced. Not only is efficiency increased, as explained, but the first cost of the machine is reduced, since the renewable face block 87 may be composed of hard steel while the paddle body 85 may be of cheaper material as a lower grade of steel.

In operation the machine combines a regulated air and coal feed at one end and at the other end a suction fan of low pressure and power receiving the pulverized materials and discharging them centrifugally. In the first pulverizing chamber 51 any metal and other heavy material not removed in the separating chamber will be thrown down centrifugally into the extension 14. The entering fuel is

struck by the paddles and thrown into whirling rotation of high speed. The fast rotation creates high centrifugal pressure so that the materials, especially the heavier particles, are kept near the periphery or lining 17 of the reducing chamber. Progressive attrition of the materials is produced by the combination of delivered blows upon the particles and the surface rubbing contact under the centrifugal pressure, and the materials gradually progressing axially at the same time. Owing to the enormous centrifugal force even relatively fine particles are thrown against the lining and travel along it, producing abrasion. In this way the lining and the paddle faces take the brunt of the reducing action, and these two elements are readily and cheaply replaceable. Succeeding the first reducing chamber are the fixed vanes 60 which totally obstruct the whirling motion while permitting substantially uninterrupted axial progress. Pulverizing occurs at this point not merely by the impact of the fast whirling particles against the fixed vanes but by rubbing and attrition along the surface of the vanes and moreover by an action of throwing back of the heavier particles into the reducing chamber, permitting only the finer particles to progress, as explained in said patent. Passing from the vanes 60 the materials under treatment are again thrown suddenly into whirling motion and are further reduced by impact and attrition. The peripheral surface of the interior of the apparatus is substantially free from obstruction to axial progress. There are no rings or diaphragms and the high centrifugal pressure is maintained throughout the length of the mill up to the point where the reducing action is completed. At this point the vanes 65 operate to overcome the centrifugal pressure and permit the whirling matters to be drawn inwardly to the contracted outlet 30. The dynamic energy of the whirling matters striking against the stationary vanes 65 causes them to spread so as to reach the outlet aperture. In effect the centrifugal action is converted to a centripetal motion. The end wall 29 acts as a dam so as to confine the peripherally whirling material under high pressure or head, and the vanes 65 constitute a means of overcoming the pressure and bringing the materials to the outlet.

The suction fan, assisting the progress of the pulverized materials from the main casing and their discharge to the place of use, is preferably of low power and pressure notwithstanding that it partakes of the high speed of the shaft 25. An ordinary type of fan, or one of the full diameter of the paddles might result in excessive pressure or suction and tend to extract the whirling matters from the main casing faster than is consistent with efficiency and fineness of reduction.

65 I have found that a fan of not over three

fourths of the diameter of the reducing devices gives satisfactory results. It keeps the air and materials in progress but avoids excessive suction. Maximum internal centrifugal pressure is thus maintainable, the diverting vanes 65 operating to bring the materials to the outlet, and the fan operating upon them for final centrifugal discharge. This refers to the blades 76 and one feature thereof is their relatively small size and their adjustability of angle.

The disclosed fan as a discharge means for a pulverizing mill can be advantageously used with other types of mill than the impact mill herein disclosed, for example with ball mills, roller mills. One duty of such a fan is to maintain the progress of the whirling matters, coal dust or other material in suspension in air, through the pulverizer and its outlet, and a second duty is to deliver these materials to the furnace or other place of use, and frequently to provide and mix therewith supplemental air of combustion. These two functions are in some respects quite different and the best results are found to be attainable by a separation of functions as herein disclosed, enabling the materials being treated to be handled and discharged separately from the supplemental air. A low suction and pressure is desirable for the coal dust or other material, especially when the interior of the main casing is progressively cleared for example as already described in connection with the vanes 65. On the other hand the delivery of the coal dust and air into a furnace demands enough pressure to overcome the resistance of the burners and piping, with some spare pressure to regulate distribution. The present invention gives satisfactory results for both purposes and this is effected moreover by the novel fan herein operating in the usual type of fan housing annexed to the pulverizer outlet. The fan chamber, except near the periphery and discharge, is effectually divided into separate chambers by the unperforated disk 72. At the pulverizer side of this disk is what may be termed the dust chamber and at the other or outer side the air chamber. Operating in the air chamber are the whirling blades 74 which operate to draw air in through the axial inlet 36 and throw it centrifugally out through the discharge 35, with relatively high pressure and rate of flow. The solid materials or dust never reaches the air chamber or contacts the air blades, but is handled entirely separately in the dust chamber. The removable dust blades 76 thereby take all the brunt of the wear from the progressing solid materials, enabling the fan to be renewed by merely replacing these parts, thus greatly minimizing upkeep expense.

The swivelled attachment of the dust blades 76 permits the suction and pressure to be adjusted to the conditions. Experi-

ments have indicated that the nearer the blades 76 are set to a tangential position the finer will be the pulverization. Thus the adjustment shown in Fig. 4 gives slower discharge and finer pulverization than that shown in Fig. 3, which will result in coarser pulverization but increased capacity of output. The arrangement thereby permits the machine to be adjusted in accordance with the material being ground and the desired fineness of product, the angle of the dust blades to be set to the most advantageous angle.

It will be observed that the adjustment of the dust blades and the resulting discharge of dust does not affect the discharge of air by the air blades 74. The two actions are independent up to the point where the discharged matters meet and mix in the general discharge outlet 35. The division of the fan chamber into two subchambers and the separation of the functions of the fan as described may be brought about in various ways. The dust blades could be made as integral extensions of the air blades, and the disk 72 adjusted axially to relatively increase the size and action of the dust blades and decrease those of the air blades, and vice versa. It is to be understood that dampers may be employed to regulate the admission of supplemental air, or the flow of the combined materials to the furnace, and such regulations can be made without affecting the pulverizing action. Ordinarily an adjustment of air flow or discharge by the fan would cause a change in the fuel outflow and thereby alter the actions within the pulverizer; whereas with the present invention even very high air pressures can be supplied for distribution to combustion points without substantially altering the constancy of the action and progress through the pulverizer.

It will thus be seen that I have described a pulverizing machine embodying the principles and attaining the objects of the present invention; but as many matters of method, operation, structure, combination, arrangement and detail may be variously modified without departing from the principles of the invention it is not intended to limit the same to such matters except so far as set forth in the appended claims.

What is claimed is:

1. Outfeeding means for pulverizing machines comprising a casing, a shaft rotatable therein, a disk on the shaft separating the interior of the casing into a dust chamber and an air chamber, dust blades at the dust side of the disk and air blades at the opposite side of the disk, the dust blades being angularly disposed with reference to the air blades.

2. A fan as in claim 1 and wherein the dust blades are detachable and removable independently of the air blades.

65 3. A fan as in claim 1 and wherein the dust

blades consist of angle pieces arranged to project laterally, with means for adjusting their angular relationship to the air blades.

4. A fan for feeding pulverized material, comprising a casing, a shaft rotatable therein, a disk on the shaft separating the interior of the casing into a dust chamber and a wider air chamber, radially disposed air blades secured to the air side of the disk, and nonradial dust blades secured to the opposite side of the disk, said dust blades being adjustable to different angles whereby to vary the feeding action of the fan.

5. A fan as in claim 4 and wherein the disk, air blades, and dust blades constitute a rotor of considerably smaller diameter than the interior of the casing.

In testimony whereof, I have affixed my signature hereto.
